COMPACT BAG

Alfred F. Reilly, North Attleboro, Mass., assignor
to Evans Case Company, a corporation of
Massachusetts

Application May 8, 1936, Serial No. 78,574

16 Claims. (Cl. 132—79)

My present invention relates to evening and afternoon bags and the like, and has particular reference to a novel construction of compact pouch or reticule.

5 Bags of standard type for evening and for afternoon wear are relatively large, and have compartments in which a compact, a handkerchief, a lipstick, coins, keys, and the like may be carried. These bags are quite bulky, and it is therefore usual amongst the younger feminine set to either carry a small evening bag, or separate vanities, coin and key containers, and the like, which are taken care of by the escorts.

10 It is the principal object of my invention to provide a small, convenient pouch or reticule which contains a complete compact and which also has space for a handkerchief, keys, coins and the like, and a folding comb if desired, whereby there is no need for either carrying a 15 small evening bag or separate containers.

It is a further object of my invention to provide a pouch which has a compact arrangement that facilitates quick and effective use.

20 With the above and other objects and advantages in view, my invention consists of a novel arrangement of parts more fully disclosed in the detailed description following, in conjunction with the accompanying drawings, and more specifically defined in the claims appended thereto.

25 In the drawings,

Fig. 1 is a plan view of the novel bag;

Fig. 2 is a view similar to Fig. 1, the top being open;

30 Fig. 3 is an elevation detail showing the top in closed position;

Fig. 4 is a view similar to Fig. 2, the vanity cover being in open position, parts being broken away;

35 Fig. 5 is a view similar to Fig. 4, the rouge cover and the powder cover being in open position;

Fig. 6 is a side view, the top being open, with parts in section;

40 Fig. 7 is a plan view of the top base;

Fig. 8 is a side view thereof, parts being broken away;

Fig. 9 is a plan view of the powder receptacle, the cover being broken away;

45 Fig. 10 is a section on the line 10—10 of Fig. 9, the cover being open;

Fig. 11 is a plan view of the rouge container, the mirror lid being fragmentary, and in open position;

50 Fig. 12 is a section on the line 12—12 of Fig. 11;

Figs. 13 and 14 are respectively plan and side views, the side view being broken away, of the powder container lock member;

55 Fig. 15 is a bottom plan view of Fig. 9; and

60 Fig. 16 is a section on the line 16—16 of Fig. 6.

Referring to the drawings, the bag 20 includes a rim 21 to which a top 22 is hingedly connected, the rim 21 having a guard 23 within which a spring catch 24 secured to the top is adapted to enter and releasably engage the outer edge 25 5 of the ring. The rim, see Figs. 6 and 16, is U-shaped, with an annular support ring 26 locked between the sides of the rim and having a depending flange 27 with spaced openings 28 in which a spiral coil 29 is wound, a mesh pouch 10 30 and an inner textile liner 31 being secured to the spiral coil, whereby a flexible container is provided suitable for keys, coins, a handkerchief, a folding comb, and other similar articles.

The top 22 is essentially a complete compact; 15 it comprises an outer portion 32 which may be figured, enamelled, plated, or otherwise ornamented, and an annular inner wall 33 which is secured to the outer portion 32 at its edge and diverges from the outer portion to provide a 20 powder housing. A circular cup 34 is seated therein as hereinafter explained, and has an opening 35 in the base 36 to permit access to the powder, a cover 37 being hinged to the base as indicated at 38, and having a catch 39 cooperating with a latch opening 40 in the base, the cover having a finger tab 41 and being recessed as at 42 to receive a powder puff, the edge of which fits under the tab 41. A closure 42 is provided for the cup 34, comprising an ornamented disk 30 43 which is hinged to the rim 44 of the cup 34, as indicated at 45, and has a spring latch 46 adapted to engage with a catch opening 47 in the rim 44, and also a finger tab 48. The closure includes a container 49 for a rouge cake, formed by mounting a U-shaped ring 50 thereto, and a lid 51 hinged to the ring edge as indicated at 52, the container being of sufficient depth to also accommodate a rouge pad if desired. The rouge cake has a metal plate backing, and is releasably held in place by the downwardly pointed inner edge of the ring and by a small finger 53. The lid 51 has a finger engageable tab 54, and is adapted to be releasably secured to the container, which has a spring catch 55 for engaging the edge of the lid. The lid front is highly polished to function as a mirror.

The parts are stamped from sheet metal, whereby the cost of manufacture and of assembly is low. The cup 34 has an exterior locking member 56 of similar form, and has a flanging upper edge 57 against which the locking member seats, and tabs 58 which are bent over to hold the locking member in place, the locking member having snap detents 59 struck outwardly and spaced about its upper edge to lock beneath the edge 58 of the annular wall 33.

All the exposed parts may be suitably ornamented; the annular wall 33 may have an impressed design, for example, and the closure disk 60

may be similarly ornamented. The parts are readily assembled, thus reducing the cost of manufacture and repair.

It is thus evident that the novel construction 5 is very compact and complete, comprising a flexible bag adapted to hold small articles, including a handkerchief, and a cover which has powder and rouge containers and a mirror.

While I have described a specific embodiment 10 of my invention, it is obvious that the concept may be applied to different types of bags, that different materials may be used for the pouch and other parts, that the parts may be ornamented, enamelled, or plated in any desired manner, and that different arrangements of the 15 containers may be made to suit the requirements for different designs, without departing from the spirit and the scope of the invention as defined in the appended claims.

20 I claim:

1. In combination, a bag having an opening, and a cover for said opening, said cover having a compartment, and a closure for said compartment comprising an additional compartment 25 which lies generally above the closure and extends into the first mentioned compartment when the device is closed.

2. In combination, a bag having an opening, and a cover for said opening, said cover having a 30 compartment, and a closure for said compartment comprising an additional compartment having a hinged lid which lies within the first mentioned compartment when the device is closed.

3. In combination, a bag having an opening, and a cover for said opening, said cover having a compartment, a cup having an opening communicating with said compartment, a hinged cover seated in said cup for said opening, and 40 a closure for said cup.

4. In combination, a bag having an opening, and a cover for said opening, said cover having a compartment, a cup having an opening communicating with said compartment, a hinged cover seated in said cup for said opening, and a closure for said cup, said closure having an additional compartment.

5. In combination, a bag having an opening, and a cover for said opening, said cover having 50 a compartment, a cup having an opening communicating with said compartment, a hinged cover seated in said cup for said opening, a closure for said cup, said closure having an additional compartment, and a hinged lid for said additional compartment.

6. In combination, a bag having an opening, and a cover for said opening, said cover having a compartment, a cup having an opening communicating with said compartment, a hinged 60 cover seated in said cup for said opening, a closure for said cup, said closure having an additional compartment, and a hinged lid for said additional compartment, said hinged lid including a mirror.

7. In combination, a bag having an annular rim, a flexible container secured to said rim, and a cover hinged to said rim, said cover having a compartment, and a closure for said compartment comprising an additional compartment 70 which lies generally above the closure and extends into the first mentioned compartment when the device is closed.

8. In combination, a bag having an annular rim, a flexible container secured to said rim, and

a cover hinged to said rim, said cover having a compartment, and a closure for said compartment comprising an additional compartment having a hinged lid which lies within the first mentioned compartment when the device is 5 closed.

9. In combination, a bag having an annular rim, a flexible container secured to said rim, and a cover hinged to said rim, said cover having a compartment, a cup having an opening communicating with said compartment, a hinged cover seated in said cup for said opening, and a closure for said cup.

10. In combination, a bag having an annular rim, a flexible container secured to said rim, and a cover hinged to said rim, said cover having a compartment, a cup having an opening communicating with said compartment, a hinged cover seated in said cup for said opening, and a closure for said cup, said closure having an additional 20 compartment.

11. In combination, a bag having an annular rim, a flexible container secured to said rim, and a cover hinged to said rim, said cover having a compartment, a cup having an opening communicating with said compartment, a hinged cover seated in said cup for said opening, a closure for said cup, said closure having an additional compartment and a hinged lid for said additional compartment.

12. In combination, a bag having an annular rim, a flexible container secured to said rim, and a cover hinged to said rim, said cover having a compartment, a cup having an opening communicating with said compartment, a hinged cover seated in said cup for said opening, a closure for said cup, said closure having an additional compartment and a hinged lid for said additional compartment, said hinged lid including a mirror.

13. In combination, a bag having an annular rim, a flexible container comprising lined metallic mesh and secured to said rim, and a cover hinged to said rim, said cover having a compartment, and a closure for said compartment comprising an additional compartment which lies generally below the cover and extends into the first mentioned compartment when the device is closed.

14. In combination, a bag having an annular rim, a flexible container comprising lined metallic mesh and secured to said rim, and a cover hinged to said rim, said cover having a compartment, and a closure for said compartment comprising an additional compartment having a hinged lid which lies generally above the closure and extends into the first mentioned compartment when the device is closed.

15. In combination, a bag having an opening, and a cover for the opening, the cover having a compartment, a cup having an opening communicating with the compartment, a hinged cover seated in the cup for the opening, and a closure for the cup, the closure having an additional compartment extending into the cup.

16. In combination, a bag having an opening, and a cover for the opening, the cover having a compartment, a cup having an opening communicating with the compartment, a hinged cover seated in the cup for the opening, a closure for the cup, the closure having an additional compartment extending into the cup, and a hinged lid for the additional compartment.

ALFRED F. REILLY.
